UNITED STATES PATENT OFFICE

HERBERT W. PENROSE, OF YERINGTON, NEVADA, ASSIGNOR OF ONE-FOURTH TO MATHEW R. PENROSE AND ONE-FOURTH TO CLARK J. GUILD, BOTH OF YERINGTON, NEVADA

SIGN

Application filed March 24, 1931. Serial No. 524,911.

This invention relates to improvements in signs and pertains particularly to a sign so designed that the lettering thereof will stand out clearly and distinctly in the daytime as well as at night when a light is thrown thereon.

The primary object of the present invention is to provide a sign in which the letters are formed of rod like glass which are inset in the face of the sign and which have light reflecting bodies about the backs thereof so as to make the letters stand out distinctly, particularly when a light is thrown onto the sign.

Another object of the invention is to provide novel means for retaining letters of glass in the receiving recesses therefor in the face of the sign, whereby anyone of the letters may be removed for replacement when necessary or for any other purpose.

Other objects and advantages of the present invention will become apparent from a consideration of the following detailed description taken in connection with the accompanying drawings forming a part of the present invention with the understanding, however that the invention is not confined to any strict conformity with the showing of the drawings but may be changed or modified so long as such changes or modifications mark no material departure from the salient features of the invention as expressed in the appended claims.

In the drawings:

Figure 1 shows one letter in front elevation in a sign constructed in accordance with the present invention.

Figure 2 is a view in rear elevation of the letter shown in Figure 1.

Figure 3 is a sectional view taken on the line 3-3 of Figure 1.

Figure 4 is a sectional view similar to Figure 3 but showing a modified form of means for holding the letter in place.

Figure 5 is a sectional view through a portion of a sign in which the back or base structure is of wood, showing the manner in which the letter is set therein.

Referring more particularly to the drawings wherein like numerals of reference in-

dicate corresponding parts throughout the several views, the numeral 1 indicates a portion of a sign board constructed in accordance with the present invention and formed of sheet metal material. In constructing the signs of sheet metal the metal is pressed to form pockets or channels therein such as the U-shaped channel 2, which is illustrated, to receive the removable portion of the letter. In the illustration of the present invention the letter U is shown and the metal body 1 of the sign has a U-shaped pocket or channel pressed in the face thereof, this channel, as previously stated, being indicated generally by the numeral 2. In this pocket there is placed from the front of the sign the glass letter U, which is indicated by the numeral 3.

As shown in Figure 3 the body of the letter, while it is formed of a rod of glass, is not of circular cross section. The rear portion is of greater diameter than the front portion of the letter, thus forming, where the portions join the shoulders 4. The rear or enlarged portion of the letter is encased by a reflector 5, the longitudinal edges of which are turned inwardly, as indicated at 6, over the shoulder 4 of the letter body.

After the letter body with the reflector 5 is placed in position in the channel or pocket 2 formed therefor in the metal board of the sign, it is held in place by shiftable latches 7 which are secured against the rear face of the sign body 1 by the screws 8. These latches have reduced or pointed ends 9 which pass through slots 10 formed in the channel 2 adjacent thereto so that the points 9 may engage against the shoulders 4 of the letter and thus prevent it from coming out of its channel. After the latches have been moved into letter engaging position the screws 8 may be drawn up tight to prevent them from shifting.

From the foregoing it will be readily seen that with a sign constructed in accordance with the present invention the letters thereof will stand out distinctly when a light is thrown thereon, because of the reflecting backing 5 of each letter. Because of this backing and the manner in which the letter

is placed in position so that substantially half of the glass letter projects from the face of the sign the lettering will also stand out distinctly in daylight or when a light is not thrown thereon. In order however, to enhance the attractiveness of the sign, the face of the sign board 1 about each letter may be outlined with a paint of suitable color, as indicated at 11.

10 In Figure 4 a modified form of holding means is illustrated, by which the letter is held in position in its socket. In this form the securing latch may be in the form of a bowed clip 12 which has each end turned inwardly forming a tongue 13. Intermediate its ends, this clip is provided with an aperture 14 which receives a threaded stud 15 carried by the letter receiving pocket, when the latch is slipped into position. A 20 nut 16 engaging the stud 15 serves to hold the latch against movement.

Figure 5 illustrates a portion of a sign in which the back board is of wood. The wood body is indicated generally by the numeral 25 17 and in the face of this there is formed the pocket 18 which conforms in outline to the letters which it is to receive. The letter itself is of course, formed of glass and is of the same cross sectional design as described 30 in connection with the preferred form so as to form the shoulders 19. The shoulders, when the letter is in position in the recess 18 lie beneath the face of the sign so that suitable latch members 20 upon the face thereof 35 may be employed for engaging the shoulders to hold the letter in position. In this form the latch may be simply rotated upon a holding screw 21, in order to bring the proper end in position over the bolt 19, after which 40 the screw may be tightened to prevent the latch from being accidentally moved.

From the foregoing description it will be readily seen that a sign constructed in accordance with the present invention may have 45 any of its letters removed in the event that they become broken, for replacement, without disturbing in any manner the other letters or any other part of the sign structure. It will also be understood that the glass of which 50 the letters are formed may be transparent or colored as desired, and the backing plates or reflectors 5 may be correspondingly colored, or if desired, the backing for the letters may be colored while the glass may be left clear 55 so as to give a color effect to the lettering.

Having thus described my invention, what I claim is:

1. In a sign structure, a sign board, a letter of glass, said sign board having a recess 60 in the face thereof designed to receive, and shaped to conform to the configuration of, the letter, and means for detachably securing the letter in the recess.

2. In a sign structure, a board, a letter 65 formed of rod like material of a transpar-

ent character, said board having a recess in the face thereof designed to receive, and conforming to the contour of, the letter, said letter having shoulders at diametrically opposite points, and latch elements carried by 70 the board and engaging over said shoulders to maintain the letter in position in the recess.

3. In a sign structure, a sign board, a letter of glass, said sign board having a recess 75 in the face thereof designed to receive, and shaped to conform to the configuration of, the letter, and means for detachably securing the letter in the recess, and a backing for said letter conforming to the contour of the 80 rear face thereof and positioned thereagainst, and said backing having the face adjacent the letter polished.

4. In a sign structure, a board, a letter formed of rod like material of a transparent 85 character, said board having a recess in the face thereof designed to receive, and conforming to the contour of, the letter, said letter having shoulders at diametrically opposite points, and latch elements carried by 90 the board and engaging over said shoulders to maintain the letter in position in the recess, and a backing disposed against the rear face of the letter and having connection with 95 said shoulders to maintain it in cross contact with the letter, the face of the backing adjacent the letter being polished.

5. In a sign, a sheet metal body, a letter, a pocket pressed in the face of the body to receive said letter, said pocket being of the same 100 configuration as the letter, and latch members shiftably mounted upon the rear face of the body and extensible through the wall of the pocket to engage the letter to maintain it against displacement.

6. In a sign, a sheet metal body, a letter of transparent material, said body having a pocket pressed in the face thereof conforming to the contour of and designed to receive the letter, a reflector backing for said letter, said backing being housed in the pocket, and latch members shiftably mounted upon the rear face of the body and extensible through apertures in the wall of the pocket and engaging the letter to prevent its displacement 115 from the pocket.

7. In a sign, a sheet metal body, a letter of transparent material, said body having a pocket pressed in the face thereof conforming to the contour of and designed to receive the letter, a reflector backing for said letter, said backing being housed in the pocket, and latch members shiftably mounted upon the rear face of the body and extensible through apertures in the wall of the pocket and engaging the letter to prevent its displacement 120 from the pocket, and shoulders formed at diametrically opposite sides of the letter 125 for engagement by said latch members.

8. In a sign, a back board, a letter formed of glass and having semi-circular front and back portions, said back portion being of greater radius than the front portion, a shoulder being formed at the point of joinder of the portions, a pocket formed in the face of the back board conforming to the contour of the letter and designed to receive the same, the pocket being of a depth to receive the back portion of the letter and the shoulders thereof, a reflector covering of the back portion of the letter and having edges engaged over said shoulder, and latch members carried by the back board and engageable over said shoulders to maintain the letter in position.
